UNITED STATES PATENT OFFICE.

LAURA L. SCHLENSKER, OF EVANSVILLE, INDIANA.

GONG-PIANO.

1,134,351.

Specification of Letters Patent.

Patented Apr. 6, 1915.

Application filed November 15, 1913. Serial No. 801,251.

To all whom it may concern:

Be it known that I, LAURA L. SCHLENSKER, a citizen of the United States, residing at Evansville, in the county of Vanderburgh and State of Indiana, have invented 5 certain new and useful Improvements in Gong-Pianos, of which the following is a specification, reference being had to the accompanying drawings.

10 This invention comprehends certain new and useful improvements in musical instruments and has for its primary object to provide a new and improved form of piano in which gongs are substituted for the strings 15 now employed.

With the above and other objects in view, my invention consists in certain novel constructions, combinations, and arrangements of parts to be hereinafter more fully described, claimed, and illustrated in the accompanying drawings, in which,

20 Figure 1 is a transverse vertical section through a musical instrument constructed in accordance with my invention; and Fig. 25 2 is a fragmentary detail front elevation with the front of the casing removed.

Referring more specifically to the drawings in which similar reference characters designate corresponding parts throughout 30 the several views, 1 designates the gongs which have their lower ends coiled, as shown at 2, while their opposite ends are extended vertically, as shown at 3, the extremities of said ends 3 being flattened, as shown at 4, 35 and engaged in sockets 5 in the lower face of the gong supporting beam 6. The flattened extremities 4 of the gongs are held in position in the sockets 5 by set screws 7 or other suitable means.

40 The metal beam 6 extends longitudinally of the piano casing within the same and in spaced relation to the back of the casing and is connected to said back by supporting

rods 8, only one of which is shown. Dampers 9 are adapted to contact with the lower coiled portions of the gongs, and hammers 12 are designed to strike the vertically disposed portions of the gongs above the dampers when operated by means of the keys. Operatively connecting the hammers and dampers with the keys are the elements of an ordinary upright piano action, which will be well understood by anyone versed in the art to which this invention appertains, and hence a detailed description of these elements is deemed unnecessary. It will be understood that when the keys are depressed, the hammers will strike the gongs and sound the notes and that when the hammers drop back against the rest rail 22, the dampers 9 will be brought into play.

What I claim is:—

A piano of the character described, including a casing, an action therein embodying key-operated hammers and dampers, a beam within the casing and extending longitudinally thereof in a horizontal position in spaced relation to the back of the casing, supporting rods connecting said beam to the back of the casing, the beam being provided with downwardly opening sockets, and gongs formed with flattened ends received and secured in said sockets, the gongs extending downwardly from said ends in substantially vertical position and being coiled at their other ends, the hammers being arranged to strike the vertical portions of the gongs and the dampers being arranged to contact with the coiled portions thereof.

In testimony whereof I hereunto affix my signature in the presence of two witnesses.

LAURA L. SCHLENSKER.

Witnesses:

SEBASTIAN HEURICH,
WILLIAM S. HEURICH.
